UNITED STATES PATENT OFFICE.

JOHN F. McCOMB, OF KOKOMO, INDIANA, ASSIGNOR TO CONTINENTAL STEEL CORPORATION, OF KOKOMO, INDIANA, A CORPORATION OF INDIANA.

DESIGN FOR A DISPLAY RACK.

Application filed March 13, 1929. Serial No. 30,453. Term of patent 14 years.

To all whom it may concern:

Be it known that I, JOHN F. McCOMB, a citizen of the United States, residing at Kokomo, in the county of Howard and State of Indiana, have invented a new, original, and ornamental Design for a Display Rack, of which the following is a specification, reference being had to the accompanying drawing, forming part thereof.

The figure is a perspective view of the display rack, showing my new design.

What I claim is:—

The ornamental design for a display rack, as shown.

JOHN F. McCOMB.
